UNITED STATES PATENT OFFICE.

PHILIP E. SARSFIELD, OF NEW YORK, N. Y.

COIN-COUNTER.

SPECIFICATION forming part of Letters Patent No. 357,635, dated February 15, 1887.

Application filed July 20, 1886. Serial No. 208,580. (No model.)

To all whom it may concern:

Be it known that I, PHILIP E. SARSFIELD, a citizen of the United States, residing at New York city, in the State of New York, have invented certain new and useful Improvements in Conductors' Money-Boxes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 The special object of the invention is to provide car-conductors with a money-box from which they can promptly and easily make change.

Figure 1 of the drawings is a vertical cross-section; Fig. 2, a longitudinal vertical section; Fig. 3, a perspective view of the inside mechanism, and Fig. 4 a perspective view of the ejector.

In the drawings, A represents the money-box, which consists of the three compartments a a' a'' . In the first stand the money-tubes B, varying in size to suit the different denominations of coin, and placed directly under the slits or inlets a^3 . In the rear compartment, a' , is supported a plate, C, having the parallel flanges c c' , oppositely slotted at c' , and provided with the excision C'. The front compartment, a'' , is a money receiver and conveyer, slotted at a'' to permit the passage therethrough of the ejectors E to the outside of the box. The ejectors E are turned at the rear, folded parallel to the body thereof, and provided with the arc pieces e, which are held under the coins by the surrounding spiral springs F until the 40 ejectors are pushed from the outside and the resistance of the springs overcome.

Between the bottoms of the tubes B and the smooth upper surface of plate C are front and rear slots, c^2 c^3 , the latter to allow the arc pieces 45 e to move in and out of the tubes, while the

former permit the coin to be ejected by the spring force into the front conveyer, a^2 . The latter is provided with a spring-latched slide or door, G, which on a slight pressure permits the coin to fall into the conductor's hand. 50

The money-box has preferably a front door, H, hinged at h and spring-latched at h' , so that the internal mechanism can be conveniently inserted or removed.

The object of the excision C' in the plate C 55 is to allow the ejected coin, which strikes the upper part of the front of the conveyer, to fall through to the bottom thereof, so that when the conductor is ready for it he slightly tilts the box to one side. 60

The money-box is supported from the neck of the conductor by any suitable flexible connections made fast to the rings a^5 on the inner side of the compartment a.

Of course I am aware that coin has been 65 dropped in conductors' money-boxes and ejected to the outside in till-boxes; but

What I claim as new, and desire to protect by Letters Patent, is—

1. A conductor's fare box and money-changer 70 consisting of a top, rear, and front compartment, the top one slotted at a^3 , having a hinge-door, H, and containing the tubes B, the front one slotted at a'' , having spring-ejectors E e, and provided with a spring-catch door, G, and 75 the rear one containing the excised, flanged, and oppositely-slotted plate C, all substantially as shown and described.

2. In a conductor's fare-box and money-changer, the plate C, and spring-ejectors E e, 80 combined with the compartment a'' , said plate being cut out at C', flanged at c c' , and slotted oppositely at c' , as and for the purpose described.

In testimonay whereof I affix my signature in 85 presence of two witnesses.

PHILIP E. SARSFIELD.
